UNITED STATES PATENT OFFICE.

GEORGE E. BERNECKER, OF MILWAUKEE, WISCONSIN, ASSIGNOR TO STANDARD ACCESSORY CORPORATION, OF MILWAUKEE, WISCONSIN, A CORPORATION OF WISCONSIN.

PHONOGRAPH-LIGHTING ATTACHMENT.

1,352,779.

Specification of Letters Patent. Patented Sept. 14, 1920.

Application filed April 30, 1919. Serial No. 293,704.

To all whom it may concern:

Be it known that I, GEORGE E. BERNECKER, a citizen of the United States, and resident of Milwaukee, in the county of Milwaukee and State of Wisconsin, have invented new and useful Improvements in Phonograph-Lighting Attachments, of which the following is a description, reference being had to the accompanying drawings, which are a part of this specification.

The present invention relates to a lighting attachment for sound reproducing machines.

It is usually difficult to obtain proper light for sound reproducing machines to change the records and needles and apply the needles to the records in operating the machine.

This invention has for one of its objects to provide an improved lighting means which may be readily applied to a sound reproducing machine to furnish the required light.

Another object is to provide an improved lighting attachment which is normally inactive, but which is adapted to be operated when desired by the operator.

Another object is to provide such a lighting means which is capable of ready attachment to sound reproducing machines of all types.

A further object is to provide a lighting attachment also capable of use in connection with player pianos, the same being secured in the roll or record compartment.

With the above and other objects in view which will appear as the description proceeds, my invention resides in the novel construction, combination and arrangement of parts substantially as hereinafter described, and more particularly defined by the appended claims, it being understood that such changes may be made in the precise embodiment of the herein disclosed invention as come within the scope of the claims.

In the accompanying drawing I have illustrated one complete example of the physical embodiment of my invention constructed according to the best mode I have so far devised for the practical application of the principles thereof, and in which:

Figure 1 is a perspective view of a portion of a sound reproducing machine with my lighting attachment attached thereto;

Fig. 2 is a front elevation of my attachment;

55

Fig. 3 is a bottom view of my attachment, parts being broken away and in section to more clearly illustrate details of construction;

Fig. 4 is a side view thereof, the light 60 deflecting cap being in section;

Fig. 5 is a transverse sectional view through my attachment taken on the line 5—5 of Fig. 2;

Figs. 6 and 7 are detail views of modified 65 forms of light deflecting caps for adapting my attachment for use with various types of sound reproducing machines; and

Fig. 8 is a further modified form of light 70 deflecting cap used with my attachment when the same is fixed to a player piano.

The sound reproducing machine to which the invention is applied will first be briefly described.

It comprises a frame or box 1 containing 75 apparatus for supporting and rotating the flat disk record 2. Bearing upon the disk is a needle 3 carried by a sound box 4 pivotally secured to an arm 5 swingingly supported by the frame 1.

80

The position of my attachment relative to the sound reproducing mechanism may vary according to the style of machine with which it is used, but in the present instance the same is secured to the side wall 6 of the 85 frame 1, as illustrated in Fig. 1. My attachment comprises a rectangular supporting panel 7 provided with apertures 8 for receiving the fastening means for securing the panel to the frame.

90

The panel 8 has its rear side recessed as at 10, its side walls grooved as at 11, and its front side provided with an upstanding boss 12 which is tapered near its base to provide a shoulder 13 for the purpose hereinafter 95 described. The panel is apertured centrally through its boss 12 to receive a lamp socket 14, said socket being grounded to the panel and having insulated therefrom and centrally located in its lower closed end a contact 15 adapted to engage the central contact 16 of an electric lamp 17 secured in said socket, the screw end 18 of the lamp being removably mounted in the socket as is common practice.

100

Slidably mounted in the groove 11 in one

105

side wall of the panel is a switch arm 19 retained in the groove by means of a fastening 20 passing through elongated slot 21 of the switch arm and threadably engaging the panel. The switch arm has one end bent laterally as at 22 to provide a finger engaging portion, and has its other end bent to provide a raised portion 23 and an outer switch finger 24, the raised portion 23 being adapted to momentarily engage a contact 25 insulated from the panel by sleeve 26 when the finger 24 is depressed, and the switch finger 24 forming a fixed or permanent contact with contact 25 when the switch is moved to the left its full limit of movement, with reference to Fig. 3, by the finger engaging portion 22.

Feed wires 27 have one end secured to the contact 15 and contact 25, and their other ends secured to a battery 28 located in any convenient position relative to supporting frame 1.

Referring more particularly to Fig. 3, it will be readily seen that when the switch arm engages contact 25, the current from battery 28 is supplied to the lamp 17 through said contact and the switch arm, then through the side wall of end 18 of the lamp, the other terminal 15, and thence back to the battery, completing the circuit. The wires 27 are secured to the contacts 15 and 25 by means of lock nuts 29 of conventional construction.

In order to adapt my attachment for use with the various styles and makes of sound reproducing machines, the wires 27 are led into recess 10 through an aperture 30 in one side wall thereof, and extending from said aperture is a slot 31 permitting the wires 27 to be removed from aperture 30 without disengaging them from their terminals whereby the same may extend downwardly from the recess 10, should it be desired to secure the panel to the base 6' of the frame 1, and have the wires project through said base to battery 28 which may be disposed therebeneath.

When my attachment is used with the type of sound reproducing machines illustrated in Fig. 1, a light deflecting cap 32 is used, having its outer end centrally apertured as at 33 to throw the light upon the needle, said cap having its inner end engaging boss 12 and provided with a friction lug 34 for retaining the same in position on the lug against accidental dislodgment. When it is desired to position the panel on the base 6' or in any other desired position, the cap 32 has its aperture 33 in the side wall thereof, or any other position as depicted in Figs. 6 and 7, whereby the same will most effectively illuminate the record.

The form of light deflecting cap depicted in Fig. 8, which is provided with an elongated slot 33' is especially adapted for use in connection with player pianos, when the panel 7 is positioned in the roll compartment so as to throw the light over the music roll as the same is being played.

From the foregoing description taken in connection with the accompanying drawing it will be readily apparent that I provide a neat and compact lighting attachment for sound reproducing machines which may be lighted momentarily by simply depressing finger 24, or which may be permanently lighted by moving the switch arm to bring finger 24 in contact with contact 25. It will also be apparent that the outer face of boss 12 is tapered inwardly toward its central aperture to provide a reflector 12' for lamp 17.

What I claim as my invention is:

1. A lighting attachment for sound reproducing machines comprising a fixed panel of a conductive material and having a guide channel in one straight face thereof, a lamp having one terminal grounded to the panel and its other terminal insulated from the panel and connected with one of two electrical feed wires, a contact in the bottom of the guide channel and insulated from the panel, the other of said feed wires being connected with said contact, and a switch member mounted in said guide channel and grounded directly to the panel and movable to engage said contact.

2. A lighting attachment for sound reproducing machines comprising a panel of a conductive material having a guide channel in one straight side thereof, the rear face of the panel being recessed, an electric lamp mounted in the panel and having two terminals, one grounded to the panel and the other insulated therefrom and disposed in the recess, a contact in the bottom of the guide channel and insulated from the panel and having a terminal disposed in said recess, electric feed wires connected with the insulated terminal of the electric lamp and with said contact terminal, one side wall of the panel being apertured to permit the passage of the feed wires downwardly from the recess or through the aperture in the side wall, and a switch member mounted in said guide channel and grounded to the panel and being movable to engagement with said contact to complete the electrical circuit.

3. A lighting attachment for sound reproducing machines comprising a lamp supporting panel of substantially rectangular shape having a central groove extending along one side thereof, an electric lamp mounted in said panel and having two terminals, one grounded to the panel and the other insulated therefrom, a contact in the bottom of said groove and insulated from the panel, electric feed wires connected with the insulated terminal of said electric lamp and

with said contact, a switch arm slidably mounted in said panel groove and having an operating finger on one end thereof and a switch contact finger formed on the other end thereof, said switch having a recess therein adjacent its contact finger for making a momentary connection with said con-

tact to complete the electrical circuit and adapted, upon sliding movement in the groove, to engage its contact finger with the contact and provide a permanent connection therewith.

In testimony whereof, I affix my signature.
GEORGE E. BERNECKER.
